DESIGN FOR AN ILLUMINATED ARTIFICIAL CHRISTMAS TREE

Milton S. Dunkelberger, Dayton, Ohio

Application March 24, 1934, Serial No. 51,170

Term of patent 14 years

To all whom it may concern:

Be it known that I, MILTON S. DUNKELBERGER, a citizen of the United States, residing in the city of Dayton, in the county of Montgomery and State of Ohio, have invented a new, original, and ornamental Design for an Illuminated Artificial Christmas Tree, of which the following is a specification, reference being had to the accompanying drawing forming part hereof.

The double ring elements shown in the drawing are openings in the surface of the tree.

The figure is a perspective view of an illuminated artificial christmas tree, showing my new design.

I claim:

The ornamental design for an illuminated artificial Christmas tree, as shown and described.

MILTON S. DUNKELBERGER.
